SHOE BOTTOM MEMBER AND METHOD OF
MAKING THE SAMEJohn M. Whelton, Peabody, Mass., assignor to
United Shoe Machinery Corporation, Paterson,
N. J., a corporation of New JerseyApplication March 24, 1932, Serial No. 600,921
Renewed October 14, 1935

32 Claims. (Cl. 12—146)

This invention relates to improvements in shoe bottom members and units and to improved methods of and means for use in making the same and also to improvements in shoes and methods of 5 shoemaking. Although by no means limited thereto the invention in one of its aspects is herein exemplified in its application to the manufacture of so-called cement process shoes and particularly to shoes of that type having unusually narrow shank portions and to the making of reinforced insole or shoe bottom members and units for such shoes.

In a copending application, Serial No. 577,297, filed November 25, 1931, in the name of Karl Kilburn, there are disclosed and claimed certain improvements in shoe bottom construction and improved methods of making shoes and shoe bottom units, a purpose of which is to facilitate the lasting of the upper and the laying of the outsole 20 so as accurately to reproduce the lines of the last in the shank portion of a shoe.

Among other objects, the present invention aims still further to facilitate the attainment of the above result.

To the accomplishment of this object, as herein illustrated, the present invention, considered in one aspect, provides an improvement in methods of making reinforced shoe bottom or insole units in accordance with which a reinforced insole member, or at least one of the component parts 30 of such an insole member, is initially overmolded transversely in its shank portion to provide a transverse curvature in excess of that of the bottom of the corresponding portion of a last to 35 which the member is to be applied so as to allow for subsequent reaction or change of transverse shape of the overmolded parts, and thus to facilitate conformance of the upper and outsole to the lines of the last. As illustrated herein, the initial overmolding is effected by the use 40 of a form having a molding surface like that of the last bottom except that its transverse curvature is greater than that of the last bottom. Moreover, as illustrated and hereinafter described, the pressure of the molding operation is 45 utilized to secure an adhesive bond between the insole and the reinforcing member.

The illustrated method involves also the cutting out of a reinforcing member or heel and 50 shank piece of fibre, leather or the like, shaped in marginal contour to correspond to that of the heel and shank portions of a shoe bottom member or sole, for example, an insole and to have a front edge adapted to coincide with the "break" 55 line of the sole, i. e., the line along which the sole

"breaks" or bends as the shoe is flexed in walking; the punching of apertures either in the reinforcing member or in the insole, or otherwise recessing one of said parts, for receiving a shank stiffener and maintaining it against lateral displacement; the application of adhesive to one or both of the insole members, i. e., to the insole itself or the reinforcing member; and preferably the assembling of the insole members and the shank stiffener, prior to the simultaneous molding of said members upon the beforementioned form. As shown, a metallic shank stiffener is employed which initially has a longitudinal curvature corresponding to that of the bottom of a last for a shoe in which the insole is to be incorporated. 15 After the insole and reinforcing member have been molded to the longitudinal curvature of the last bottom and the reinforcing member has been overmolded transversely as above described the insole is transferred to the last. The molded insole unit which, as herein exemplified, is made very narrow in its shank portion for use in narrow shank shoes, may be tacked or adhesively-secured to the last and, as illustrated, an upper 20 is mounted upon the last and its margins cement-lasted over the insole to bring their edges into substantially meeting relation in the narrowest portion of the shank of the insole, after which an outsole, having a shank portion narrower than the shank portion of the insole, is laid 25 and adhesively secured to the overlasted upper margins. As illustrated too, the reinforcing member may be applied to either side of the insole but the shank stiffener in every case is illustrated as interposed between these parts so 30 that no metallic element is present upon the outer side of the insole to interfere with the operation of lasting of the upper margins, or with the formation of a satisfactory bond between the insole and the upper margins or between the upper margins and the outsole, such an arrangement being particularly advantageous in the manufacture of shoes the soles of which have exceptionally narrow shank portions as herein 35 shown. In accordance with an alternative method of operation, also illustrated herein, the desired contour of the reinforced insoles may be obtained by initially molding the reinforcing member upon a form shaped to overmold the shank portion of the member transversely, transferring the molded reinforcing member to an unmolded insole upon a last, and thereafter molding the insole and securing together the insole and the reinforcing member by the employment, for example, of a sole-laying machine of any well-known type. 40 45 50 55

Considered in another aspect the invention provides an improved shoe bottom unit resulting from the practice of the herein-described method.

5 The invention further consists in other novel method and structural features hereinafter described and pointed out in the claims.

Fig. 26 is a sectional view taken along the line XXVI—XXVI of Fig. 25; and

70 Fig. 27 is a longitudinal sectional view of a portion of a reinforced insole illustrating a still further modification.

Referring to the drawings, the improved insole unit or reinforced insole 30, best shown in Figs. 15 and 16, comprises an insole proper 32, a reinforcing member, filler piece, or heel and shank

piece 34 which may be made of any suitable moldable material, such as fiber, leatherboard or leather, and a metallic shank stiffener 36. Both the insole 32 and the reinforcing member 34 may be cut in any customary manner, for example, they may be die cut or they may be cut by a rounding operation. The cutting of the reinforcing member 34 by a rounding operation is herein illustrated in Fig. 3, wherein a knife 38 is shown in operative relation to a pattern 40 upon which the work is secured by means of a clamp plate 42. The same pattern and knife may be employed for cutting the insole 32, thereby insuring that both the insole and the filler piece shall be accurately cut to the same contour. The shank stiffener 36 15 consists of a narrow strip of resilient metal which is initially curved longitudinally to correspond to the curvature of the last to be used in making the shoe in which the insole unit is to be incorporated.

In the finished shoe it is desirable that the 20 front edge 44 of the reinforcing member 34 shall bear a predetermined relation to, herein illustrated as coinciding with the "break" line of the sole, i. e., the line along which the sole bends or flexes when the shoe is used in walking. To insure the establishment of this relation between the front edge of the reinforcing member and the insole, as herein illustrated, a gage 46 (Fig. 3) is provided upon one side of the pattern 40 for engagement with the edge of a piece of stock, such 30 as the stock 48, from which the reinforcing members are to be cut. When insoles are to be cut the pattern 40 may be reversed so as to present its opposite face to the work and thus to prevent the gage 46 from interfering with proper engagement of the pattern with the insole. In assembling the reinforcing member and the insole, the reinforcing member, which was engaged with one side of the pattern while being cut may be made to coincide with the insole, which was engaged with 40 the other side of the pattern by the simple expedient of reversing either the reinforcing members or the insole. Preferably, the marginal portion of the stock 48 from which the forward portion of the reinforcing members are to be cut 45 is initially skived or beveled so that the front ends of the reinforcing members will be correspondingly beveled to avoid the formation of an undesirable ridge in the outsole.

In order to provide for convenience in assembling and securing the shank stiffener in place in the reinforced insole unit, two apertures 50 may be formed, either in the reinforcing member or in the insole, for receiving the opposite ends of the shank stiffener. Preferably, and as herein 55 illustrated, the apertures are provided in the reinforcing member and conveniently they may be formed by means of punches 52 carried by the clamp plate 42, the punches being arranged to cooperate with the pattern 40 in cutting the apertures.

The broader aspects of my invention relating to the above-described method of assembling and securing the shank stiffener in place in the insole unit, and certain features of reinforced insole 65 construction resulting from the practice of that method, constitute the subject-matter of my divisional application, Serial No. 78,690, filed May 8, 1936.

Prior to the assembly of the shank stiffener 70 with the reinforcing member both the reinforcing member and the insole are coated with adhesive and allowed to set long enough to render the adhesive in proper condition for securing the parts together. As herein illustrated, a coating of 75

latex is applied to the insole 32 by means comprising a lower cement-applying roll 54 (Fig. 6), and an upper roll 56 arranged to cooperate with the roll 54 to feed the insole between the rolls. 5 As shown, the roll 54 is arranged to dip into a quantity of cement contained in a reservoir 58, the upper portion of the roll projecting through an opening 60 in a plate 62 which constitutes the top of the reservoir and which also serves as a 10 table for supporting the work before and after it is acted upon by the rolls. Advantageously, the insole is fed in a lateral edgewise direction to the rolls and a gage 64 is arranged to engage the heel end of the insole to determine the longitudinal 15 relation of the sole to the rolls so as to enable the cement to be applied only to the heel and shank portions of the sole. As shown, the gage 64 is capable of being adjusted to vary the location of the forward extremity of the coated area. 20 By placing the insole on the plate 62 in the proper angular relation relatively to the axes of the rolls the operator may insure that the band of cement shall terminate in a line approximately parallel to the break line of the sole. The same 25 apparatus may be employed for coating the reinforcing members and conveniently the reinforcing members may be fed endwise between the rolls. After being coated the insole and the reinforcing member appear as shown respectively in 30 Figs. 4 and 5, the cement coatings being indicated at 66 and 68, respectively.

Before the filler piece and the insole are assembled, the opposite end portions of the shank stiffener 36 are inserted through the apertures 35 50 in the filler piece and the shank stiffener is adjusted longitudinally to bring its forward end into a desired predetermined relation to, herein illustrated as substantially flush with the forward edge 44 of the filler piece. The insertion of the 40 longitudinally curved shank stiffener 36 imparts a corresponding longitudinal curvature to the filler piece 34, as shown in Figs. 8, 9 and 10. The shank stiffener 36 has struck up at its rear end a single pointed prong 70 which, during the molding 45 of the filler piece and the insole, is pressed into the filler piece so as positively to hold the shank stiffener in place. Prior to the molding operation, however, the pressure of the pointed tip of the prong 70 against the filler piece serves 50 to hold the shank stiffener against accidental endwise displacement.

The filler piece and the insole are now ready to be molded and secured together, and these 55 operations are performed, as herein illustrated, by the co-operation of a rigid form 74 with a yieldable rubber pad 76 (Fig. 11). As shown, the form 74 is shorter than the full length of the insole and is adapted to operate upon the heel and shank portions of the insole and the rear 60 portion only of the forepart. The upper or work engaging surface of the form has the same longitudinal curvature as that of the bottom of the last for the shoe in which the insole is to be incorporated. Transversely, however, the work 65 engaging surface of the form is somewhat more sharply curved than the last bottom in order to provide for overmolding of the shank portion of the insole unit. Obviously, such overmolding of the shank portion of the insole could not be 70 accomplished if the insole were to be molded upon the last. As shown in Fig. 13, the opposite sides of the form 74 are made flat to facilitate the use of gage members in connection with the form for 75 locating the filler piece and insole relatively to the form. The use of a form such as the form 74

in place of a last as one of the mold members is further advantageous inasmuch as it avoids the tying up of a large quantity of lasts during the molding of the insoles and thus avoids unnecessary interference with the normal process of manufacturing the shoes. In making the forms, it is necessary to use only a single last, the forms being graded up and down from the single last.

As herein shown, the form 74 and the pad 76 are incorporated in a machine embodying certain novel features of construction particularly adapting it for use in applying the desired molding pressure.

The illustrated machine comprises a frame including two posts 78 (Fig. 11), a stationary head 80 which is fixed to the upper ends of the posts 78 and carries the pad 76, and a reciprocatory cross head 82 which is located beneath the head 80 and is mounted to slide on the posts 78 and which carries a block 84 for supporting the form 74. The pad 76 is secured to the under side of a carrier 86 which is mounted upon the head 80 with provision for horizontal sliding adjustment relatively to the form 74 in a direction lengthwise of the latter. As shown, the carrier 86 is arranged to slide upon a horizontal bar 88 fixed to the under side of the head 80, the bar 88 being received in a groove in the carrier 86 and being held in the groove by means of gibbs 90 which overlie the opposite lateral margins of the 30 bar and serve to support the weight of the block and the pad. A set screw 92 threaded in the carrier 86 is arranged to engage the edge of the bar 88 to secure the carrier 86 and the pad 76 in 35 adjusted position with the contoured lower surface of the pad adapted to register with the correspondingly contoured upper surface of the form 74.

The block 84 is provided with a flat upper face 96 which serves to support the form 74 and the 40 form is held in place on the block 84 and positioned lengthwise relatively to the pad 76 by means of a post 98 on the block which is arranged to enter a hole 100 in the under surface of the form. The block 84 is pivotally connected to the 45 crosshead 82 so that the form may adjust itself into the proper angular position to insure full 50 surface engagement of both the form and the pad with the reinforced insole. For this purpose the crosshead 82 is provided with two spaced uprights 55 104 which are forked at their upper extremities to receive studs 106 carried by the block 84. The uprights 104 are provided also with lugs 108 which are apertured to receive the posts and thus to afford the sliding connection between the crosshead and the posts. The amount of tilting adjusting of the block 84 and the form 74 about the common axis of the studs 106 is limited by means of set screws 110 and 112 which are threaded through lugs 114 on the block and are arranged 60 to engage opposite sides of the crosshead 82, suitable lock nuts 116 being provided to secure the set screws in adjusted position. The studs 110, 112 may be relatively adjusted to cause either the heel or forepart of the shoe bottom member on 65 the form to be first engaged by the pad and thus to cause the molding pressure to progress lengthwise of the work in either direction as may be found more desirable.

In order to locate the form 74 in a position of 70 longitudinal alignment with the pad 76, locating means is provided in the form of a yoke 118 adapted to engage opposite lateral portions of the heel at the heel end of the form. The yoke 118 projects upwardly above the upper surface of the 75

form in order that it may function also to locate the filler piece and the insole with the edges of the latter in vertical alinement with the sides of the form. In order that this upwardly projecting yoke shall not interfere with the downward movement of the pad the yoke is mounted with provision for vertical yielding movement relatively to the block 84. The yoke 118 is also capable of being adjusted in a direction lengthwise of the form in order to accommodate forms of different sizes. To permit the above-described vertically yielding movements and horizontal adjustment of the yoke 118 the latter is secured to a slide 120 (Fig. 12) mounted in vertical guideways 122 in a block 124 carried at the outer end of a horizontal stud 126 (Fig. 11) which is slideable in a bore 128 in the block 84. A stud 130 projecting from the block 84 extends between lugs 132 carried by the block 124 to prevent the latter from turning about the axis of the stud 126. The slide 120 is acted upon by a spring 136 arranged to hold the slide normally in an upper position determined by engagement of the upper end of the slide with an adjustable abutment 138 carried by the block 124. Horizontal adjustment of the block 124 for the purpose of locating the yoke 118 in accordance with the size of the form is effected by means of a hand screw 140 the shank portion of which is threaded within a bore in the stud 126 and which is confined against longitudinal movement by means of a plate 142 one side of which is engaged by the head of the screw and the other side by means of a collar 144 on the screw. The crosshead 82 is adapted to be reciprocated to move the block 84 and the form 14 toward and from the pad 76 by any suitable means not herein shown.

Provision is also made for locating the insole 32 relatively to the form 14 and for locating the reinforcing member 34 relatively to the insole and the form. For this purpose the yoke 118 which engages the heel portion of the form to determine the angular position of the form upon the block 84, is arranged, as hereinbefore described, to engage also the edges at the heel ends of the insole and reinforcing member to locate these parts lengthwise relatively to the form and to center the heel portions thereof relatively to the form. In order to determine the angular relation of the insole and the reinforcing member to the form and to aline their edges with the edges of the form a pair of relatively short gage fingers 150 is provided for engagement with the opposite lateral edges of the sole and the reinforcing member, at the rear of the shank portions of the latter, and a pair of relatively long gage fingers 152 is provided for engaging the opposite lateral edges of the insole and the reinforcing member at the narrow forward extremities of the shank portions of the latter. The gage fingers 150 are pivoted upon vertical studs 156 which are carried by the vertically yieldable block 124 and the gage fingers 152 are also pivoted upon the studs 156 beneath the fingers 150, the arrangement being such that the members of each pair of gage fingers are adapted to swing horizontally toward and from each other. Each of the gage fingers 150 is provided at its free extremity with vertically elongated work engaging surfaces 158 adapting the fingers to engage not only the edges of the insole and reinforcing member but also to engage the sides of the form. The short gage fingers 150 are also provided with lips 160 which project inwardly beyond the surfaces 158 to overlie the work and positively hold it in close engagement

with the bottom of the form. Rearward extensions 162 of the short gage fingers 150 are adapted to be grasped and moved toward each other by the operator for the purpose of separating the work engaging extremities of the fingers to facilitate the placing of the insole and the reinforcing member upon the form. Downward extensions 164 of the free extremities of the fingers 150 are arranged to engage the long gage fingers 152 to separate the latter when the short fingers are separated as above described. A spring 166 connecting the short gage fingers 150 and a similar spring 167 connecting the long gage fingers 152 normally hold the gage fingers in position to perform their gaging functions, the operative positions of the gage fingers being determined by engagement of the free extremities with the opposite sides of the form.

The gage fingers 150 and 152 and the yoke 118 being mounted upon the vertically yieldable block 124 are capable of being depressed to avoid interference with the operation of the pad 76 when the latter is lowered to apply molding pressure to the work. For the purpose of depressing the yoke 118 and the gage fingers a vertically adjustable abutment 170 is carried by the pad block 86 and arranged to engage one of the pivot studs 156. While the gage fingers and the yoke are being thus depressed, inclined cam surfaces 172 (Fig. 14) at the extremities of the fingers 150 serve, by engagement with the edges of the reinforcing member, to separate these gage fingers sufficiently to withdraw the lips 160 from their overlapping relation to the reinforcing member, thereby exposing the entire upper surface of that member for engagement with the pad 76.

The above described apparatus is not claimed herein, the same being disclosed and claimed in a continuation application, Serial No. 701,814, filed December 11, 1933.

In the use of the above-described apparatus, after a form of the proper size has been placed in position upon the block 84 the operator separates the gage fingers 150 and 152 by grasping the extensions 162 of the fingers 150 and then places an insole upon the form with the coated surfaces of the insole uppermost and thereafter places a reinforcing member upon the insole with the coated surface of the reinforcing member lowermost, care being taken to engage the rear edges of both the insole and the reinforcing member with the yoke 118. The operator then releases his grasp upon the extensions 162 of the fingers 150 whereupon both sets of fingers 150, 152 are moved inwardly by their springs 166 and 167 until they engage opposite sides of the form 14. The insole and the reinforcing member will then each be positioned with its opposite edges alined with the opposite sides of the form. The machine is then operated to cause the pad 14 to descend and apply pressure to the work and thereby to secure the insole and the reinforcing member together and to mold them to the contour of the form. Preferably the form may be shaped to overmold the shank portions of the insole and reinforcing member transversely to such an extent that when the molding pressure is subsequently released and the insole has been permitted to react the transverse curvature through the shank portion of the insole will conform exactly to that of the bottom of a last, such as the last shown in Figs. 18 to 20, upon which the shoe is to be made. The extent of transverse overmolding of the work is indicated in Fig. 13 and 75

the appearance of the reinforced insole after it has been molded is shown in Fig. 15.

Upon release of the molding pressure the reinforced insole is removed from the molding machine and the opposite lateral edges along the shank portion of the insole are reduced by any suitable means not herein shown to provide the beveled surfaces indicated at 180 (Fig. 16), the angle of bevel being such as to blend with the profile of the last.

While both the reinforcing member and the insole may advantageously be overmolded transversely as above described it may in some instances be desirable to overmold only one of these parts, for example, the reinforcing member and subsequently, after the overmolded member has reacted so that its transverse curvature is the same as that of the last which is to be employed, to assemble upon the last the initially overmolded member and the other member, for example, the insole, and to utilize the pressure applied during the performance of a customary sole laying operation to effect the requisite molding of the insole and the securing together of the insole and the reinforcing member. In carrying out such a practice, and particularly if the initially overmolded part is composed of fiber or leatherboard, it has been found that the fiber or leatherboard member, after being adhesively secured to the leather member, will prevent the leather member from reacting upon release of the sole laying pressure, with the result that the unit finally produced will have the desired transverse curvature even though one of the elements constituting the unit has not been overmolded. Fig. 16 shows a unit comprising a reinforcing member 34 which has been overmolded upon a form, such as the form 74, and which has a shank stiffener 36 assembled therewith. A novel shoe bottom unit has thus been produced comprising a reinforcing member and a shank stiffener in which the reinforcing member has been molded both longitudinally and transversely to produce a surface contour corresponding to that of the bottom and last to be employed in the manufacture of a shoe in which the shoe bottom unit is to be incorporated.

The reinforced and molded insole or shoe bottom unit is now ready to be placed upon a last L upon which the shoe is to be made. The insole unit is tacked to the last in the usual manner (the insole being shown in Fig. 19 as it appears after being tacked to the last) and, as shown in Figs. 20 and 21, an upper U is cement-lasting over the insole unit, staples 182 or other suitable fastenings being employed to secure the upper to the insole during the drying of the cement. Because of the fact that the shank stiffener is located between the reinforcing member and the insole it will not interfere with the driving of the staples or other fastenings. In the narrow shank portion of the shoe, as herein shown, the overlasted upper margins substantially meet and inasmuch as there is no metallic stiffener located upon the outer surface of the insole a satisfactory bond will be obtained between the upper and the insole throughout the full width of the latter. Subsequently, when an outsole O is laid and secured by cement to the overlasted upper margins, as shown in Fig. 21, a perfect bond will be obtained between those elements throughout the full width of the outsole, even if the shoe has the particularly narrow or so-called "fiddle shank" formation shown in the drawings.

In Figs. 22, 23 and 24 there is shown a modified

reinforced insole construction in which the insole 320 is provided with a lip 184 to which the upper of the shoe is to be stapled to hold the upper in place during the drying of cement employed for securing the lasted upper to the feather of the insole, in accordance with a method of making cement lasted shoes disclosed and claimed in United States Letters Patent No. 1,932,545, granted October 31, 1933, upon application of George Goddu. The particular lipped insole herein shown, however, embodies an improved lip construction disclosed in United States Letters Patent No. 2,017,856, granted October 22, 1935, upon application of George Goddu.

In the manufacture of this modified reinforced insole unit, the reinforcing member is applied, as shown at 340, to the upper or grain side of the insole so that, instead of being located between the inner and outer soles of the finished shoe, it will be located at the upper or inner side 20 of the inner sole where, in the absence of a sock lining, it will be directly engaged by the foot of the wearer. In an insole of this type, moreover, it is convenient to punch the shank stiffener receiving apertures in the insole instead of in the reinforcing member, as indicated at 500. The opposite ends of the shank stiffener 36 will, in this instance, be threaded through the apertures 500 in the insole, thus causing the main portion of the stiffener to be located between the insole and the reinforcing member as in the form of insole hereinbefore described. The modified reinforced insole construction shown in Figs. 22, 23 and 24 and the improved method practiced in making such an insole is not claimed herein, the same being 35 part of the subject-matter of a continuation application, Serial No. 81,055, filed May 21, 1936.

Instead of securing the shank stiffener in place by inserting its ends through apertures either in the insole or in the reinforcing member the stiffener may be secured in place by tacks, the tacks, for example, being driven into the reinforcing member as indicated at 186 in Fig. 25, wherein a stiffener 360 is provided, the stiffener being fitted with the usual tack holes by having 45 no attaching prong. To insure that the stiffener 360 shall have no tendency to produce an undesirable bulge or ridge in the outsole a shallow groove 188 may be formed in the reinforcing member to receive it as shown clearly in Fig. 26. 50

It may be desirable to mold the reinforcing member by the use of the form 108 (thereby overmolding the reinforcing member transversely) without at the same time molding the insole. In this way there may be produced, for shipment 55 to shoe manufacturers, a molded shoe bottom unit comprising only a reinforcing member and a shank stiffener as shown in Fig. 18. In the use of such a shoe bottom unit, after assembly of the unit with an insole upon a last bottom, the insole may be molded and adhesively secured to the reinforcing member by the use of a sole laying machine of customary construction, after which the usual shoemaking operations may be performed to complete the 60 shoe. In practicing the above modification of the hereinbefore-described method of shoemaking the adhesive attachment to the insole of the previously overmolded reinforcing member will effectively prevent the insole from reacting upon 65 release of the insole molding pressure and thus the insole will permanently retain its transversely molded contour even though the insole itself has not been overmolded.

As shown in Fig. 18, only a single aperture 50 75

may be provided in the reinforcing member 34 for receiving the rear end of the shank stiffener 36 and an open notch or recess 501 may be provided in the forward edge portion of the reinforcing member for receiving the front portion of the stiffener. The provision of the notch or recess 501 will permit the front portion of the stiffener 36 to lie with its opposite sides substantially flush with the corresponding sides of the reinforcing member and thus to avoid the formation of any bulge due to the thickness of the stiffener in the immediate vicinity of the break line of the sole. As clearly shown in Fig. 18 the construction of the recess or notch 501 is such that the forward portion of the reinforcing member 34 is forked and the forward extremity of the stiffener 36 lies between the forwardly projecting portions of the reinforcing member which constitute the "arms" of the "fork".

20 A lipped insole of the type shown in Fig. 23 may be split from its heel end forwardly to a point in the vicinity of the ball line to form upper and lower sections or flaps, and between these sections may be disposed a molded reinforcing unit 25 comprising a longitudinally arched shank stiffener and a reinforcing member made preferably of fiber and shaped, in marginal outline, to conform to the marginal contour of the heel and shank portions of the insole. An insole split as 30 just described is shown in Fig. 27 wherein the upper and lower sole sections or flaps are indicated at 190 and 192, respectively, the shank stiffener is indicated at 194, and the reinforcing member at 196. As also shown in Fig. 27, the shank stiffener 194 is secured by suitable means, 35 such as tacks 198, to the reinforcing member 196. The reinforcing member 196 is secured by means of adhesive to the sole sections 190 and 192. The reinforced insole construction shown in 40 Fig. 27 is not claimed herein, the same being part of the subject-matter of a continuation application, Serial No. 82,283, filed May 28, 1936.

Having described my invention, what I claim as new and desire to secure by Letters Patent of 45 the United States is:

1. That improvement in methods of reinforcing insoles which consists in forming a reinforcing member for the heel and shank portion of an insole, molding said reinforcing member to a longitudinal contour corresponding to that of the bottom of the shank portion of a last while overmolding the reinforcing member transversely to compensate for reaction of the molded material in such a manner that ultimately there will 55 be imparted to the reinforcing member a cross-sectional contour accurately conforming to that of the bottom of the last, and simultaneously with said molding operations securing the reinforcing member to an insole.
- 60 2. That improvement in methods of reinforcing insoles which consists in cutting out an insole, cutting out a reinforcing member for the heel and shank portions of the insole, assembling a shank stiffener with one of said parts, over- 65 molding said part to compensate for reaction of the molded material so as to impart to said part an ultimate contour accurately conforming to that of the bottom of a last for a shoe in which the insole is to be incorporated, and securing the 70 reinforcing member and the insole together with the shank stiffener interposed between.
- 75 3. That improvement in methods of making reinforced insoles which consists in cutting out an insole, cutting out a reinforcing member for the heel and shank portions of the insole, re-

cessing one of said parts to receive a shank stiffener and hold the stiffener against lateral edge-wise displacement relatively to said part, assembling a shank stiffener with said part, overmolding said part to compensate for reaction of the 5 molded material so as to impart to said part an ultimate contour accurately conforming to that of the bottom of a last for a shoe in which the insole is to be incorporated, and securing said parts together with the stiffener interposed between them.

4. That improvement in methods of making reinforced insoles which consists in cutting out a full length insole, cutting out a reinforcing member to impart thereto a marginal contour 15 corresponding to that of the heel and shank portions of the insole, recessing said reinforcing member to receive a shank stiffener, assembling a shank stiffener with said reinforcing member, securing said reinforcing member to said insole with the shank stiffener interposed between the reinforcing member and the insole, and beveling the lateral edges of the shank portions of both the reinforcing member and the insole.

5. That improvement in methods of making reinforced insoles which consists in cutting out a full length insole, cutting out a reinforcing member to impart thereto a marginal contour corresponding to that of the heel and shank portions of the insole, recessing said insole to receive 30 a shank stiffener, assembling a shank stiffener with the insole, securing the insole to the reinforcing member with the shank stiffener interposed between them, and beveling the lateral edges of the shank portions of both the reinforcing member and the insole.

6. That improvement in methods of making reinforced insoles which consists in cutting out an insole, cutting out a reinforcing member for the heel and shank portion of the insole, forming a shank stiffener receiving recess in at least one of said parts, applying a coating of adhesive to at least one of said parts, assembling said parts with a shank stiffener interposed between them and located in said recess, and molding the 45 insole and reinforcing member to arch them transversely while utilizing molding pressure to secure them together.

7. That improvement in methods of manufacturing reinforced insoles which consists in cutting 50 a piece of stock to an outline determined by a pattern to produce an insole, utilizing the same pattern in cutting another piece of stock to produce a reinforcing member for the heel and shank portions of the insole and gaging the position of said piece of stock relatively to the pattern to locate the edge of the stock which is to constitute the front edge of the reinforcing member in a position to correspond to that of the "break" line of said insole, and securing said 60 insole and said reinforcing member together with their rear and lateral edges in alignment and with the front edge of the reinforcing member coinciding with the "break" line of the insole.

8. That improvement in methods of manufacturing reinforced insoles which consists in cutting out an insole, cutting out a reinforcing member for the insole having lateral edges of the same shape as those of the heel and shank portions of the insole and having a front edge arranged to coincide with the "break" line of the sole when the lateral edges of the reinforcing member are aligned with the lateral edges of the sole, applying a coating of adhesive to at least 70 one of said parts, assembling with the reinforce-

ing member a shank stiffener longitudinally curved to correspond to the curvature of the bottom of a last for a shoe in which an insole is to be incorporated and positioning the shank stiffener with its front edge flush with the front edge of the reinforcing member, assembling the reinforcing member and the insole with their lateral edges in alignment with the shank stiffener located between said parts, and molding said parts to adapt them to fit the bottom of the last.

9. That improvement in methods of manufacturing shoes of the type having an insole and a molded reinforcing member for the shank portion of the insole which consists in preparing one of said parts to receive a shank stiffener and to maintain the stiffener against lateral displacement, assembling a shank stiffener with said part, transversely overmolding at least one of said parts and securing said parts together with the shank stiffener between them, lasting an upper to the insole, and completing the manufacture of the shoe.

10. That improvement in methods of manufacturing shoes of the type having an insole and a reinforcing member for the shank portion of the insole which consists in preparing one of said parts to receive a shank stiffener and hold it against lateral displacement, assembling a shank stiffener with said part, transversely overmolding the insole and the reinforcing member and securing said parts together with the shank stiffener interposed between them to produce a reinforced insole unit, transferring the insole unit to a last, mounting an upper upon the last, lasting the upper margins to the insole, laying an outsole, and securing the outsole to the overlasted upper margins.

11. That improvement in methods of manufacturing shoes which consists in securing together an insole, a shank stiffener and a reinforcing member to make a reinforced insole, molding the shank portion of the reinforced insole to impart thereto a transverse curvature greater than that of the last upon which the shoe incorporating the reinforced insole is to be made to allow for subsequent reaction of the insole, and thereafter placing the reinforced and molded insole upon the last, lasting an upper and securing it to the insole, and completing the shoe in a customary manner.

12. That improvement in methods of making shoes which consists in transversely overmolding the shank portion of a reinforced insole to allow for subsequent reaction of the molded material, and thereafter applying the molded insole to a last, lasting an upper and securing it to the insole, and completing the shoe.

13. That improvement in methods of making shoes having reinforced insoles which consists in cutting out an insole, cutting out a reinforcing member for the insole having lateral edges of the same shape as those of the heel and shank portions of the insole, applying a coating of adhesive to at least one of said parts, assembling said member and said insole upon a form having a molding face shaped like the bottom of a last for a shoe in which the insole is to be incorporated except that said face is curved transversely to a greater extent than the last bottom, applying pressure to said parts to mold them to fit the form and to secure them together to make a reinforced insole, releasing the molding pressure to permit reaction of the insole, transferring

the insole to the last, lasting an upper over the insole, and completing the shoe.

14. That improvement in methods of making shoes which consists in assembling a shank stiffener and a reinforcing member for the shank portion of an insole, molding the reinforcing member to impart thereto a transverse curvature greater than that of the last upon which the shoe incorporating the reinforcing member is to be made to allow for subsequent reaction of the reinforcing member, assembling the molded reinforcing member with an insole upon a last, molding the insole to fit the last, and completing the shoe.

15. That improvement in methods of making shoes which consists in cutting a reinforcing member to the marginal contour of the heel and shank portions of an insole, assembling a shank stiffener with the reinforcing member, applying an insole to a last, placing the assembled reinforcing member and shank stiffener upon the insole with the shank stiffener between said member and the insole, molding the insole to the contour of the last bottom, lasting an upper and securing it to the insole, and laying an outsole and securing it to the upper.

16. That improvement in methods of making narrow shank shoes which consists in securing together an insole member having a narrow shank portion, a reinforcing member for the narrow shank portion of the insole member, and a shank stiffener with the shank stiffener interposed between the insole member and the reinforcing member, molding said members to the longitudinal curvature of a last bottom, thereafter assembling said molded members with an upper on a last, lasting the upper and thereby bringing the margins of the upper into substantially meeting relation in the narrowest portion of the shank of the insole, adhesively securing the upper margins to the insole, and adhesively securing to the overlasted upper margins an outsole having a shank portion narrower than that of the insole.

17. A shank stiffener unit comprising a reinforcing member for the shank portion of an insole, said member being arched both longitudinally and transversely and having a notch extending rearwardly from its front edge and an aperture spaced rearwardly from said notch, and a shank stiffener having one end extending into said aperture and its opposite end located in said notch with its sides substantially flush with the surfaces of the reinforcing member.

18. A shoe bottom unit comprising an insole member, an elongated non-metallic reinforcing member secured to said insole member, both of said members being molded to arch them longitudinally to correspond to the longitudinal curvature of a last bottom and to arch them transversely an amount not less than that of the transverse curvature of the last bottom, one of said members having a recess at one side to receive a shank stiffener, and a shank stiffener seated in said recess with the outer surface of the shank stiffener substantially flush with the surface of said member.

19. A shoe bottom unit comprising an elongated reinforcing member molded longitudinally to impart a curvature thereto corresponding to the longitudinal curvature of a last bottom and overmolded transversely to impart thereto a transverse curvature not less than that of said last bottom, said reinforcing member having an aperture therein, and an elongated stiffening ele-

ment having a portion located in said aperture and held thereby against lateral displacement.

20. A shoe bottom unit comprising an insole, a reinforcing member for the heel and shank portions of the insole adhesively secured to the insole, the shank portions of the insole and the reinforcing member being molded longitudinally to fit a last and being overmolded transversely, and a longitudinally arched shank stiffener located 5 between the insole and the reinforcing member, the reinforcing member being prepared to receive the shank stiffener and hold it against lateral displacement.

21. A shoe bottom unit comprising an insole, 15 a reinforcing member for the heel and shank portions of the insole adhesively secured to the insole, the shank portions of the insole and the reinforcing member being molded longitudinally to fit a last and being overmolded transversely, 20 and a longitudinally arched shank stiffener located between the insole and the reinforcing member, the shank stiffener being countersunk within the reinforcing member.

22. That improvement in methods of manufacturing reinforced insoles which consists in cutting out an insole, cutting out a reinforcing member for the insole shaped to coincide with the contour of the lateral edges of the heel and shank portions of the insole and having a front 25 edge arranged to bear a predetermined relation to the break line of the insole when the lateral edges of the reinforcing member are alined with the corresponding lateral edges of the insole, assembling a shank stiffener with the reinforcing member and positioning the shank stiffener with 30 its front edge bearing a predetermined relation to the front edge of the reinforcing member, and thereafter assembling and securing together the reinforcing member and the insole with their lateral edges in alinement and with the shank stiffener located between said parts.

23. That improvement in methods of making shoe bottom units which consists in assembling an insole member, a shank stiffener, and a member 45 for reinforcing the heel and shank portions of the insole member, said reinforcing member having a recess in its shank portion and said shank stiffener being positioned with its body portion interposed between said insole member and said reinforcing member and with one end portion located 50 in said recess, and thereafter adhesively securing the shank portions of said insole and said reinforcing member together and molding said shank portions both longitudinally and transversely to conform to the longitudinal and transverse curvatures, respectively, at the bottom of a last.

24. A shoe bottom unit comprising an insole member having a longitudinally and transversely 60 molded shank portion, a member for reinforcing the heel and shank portions of said insole member having a recess in its shank portion for receiving a shank stiffener, said reinforcing member having its shank portion longitudinally and transversely 65 molded to conform to the molded shank portion of said insole member and said members being adhesively secured together, and a shank stiffener having its body portion interposed between said members and having one end portion located 70 in said recess.

25. That improvement in methods of making reinforced insole units as articles of manufacture which consists in cutting out an insole, cutting out a reinforcing piece for the heel and shank 75 portion of the insole, applying a coating of ad-

hesive to at least one of said parts, assembling said parts with a shank stiffener interposed between them, molding the shank portions of the insole and the reinforcing piece to arch them both longitudinally and transversely while utilizing 5 the molding pressure to secure them together, said molding operating including an overmolding of said portions to compensate for reaction of the molded material, and thereafter beveling the opposite lateral edges of the shank portions of 10 the insole and the reinforcing piece.

26. That improvement in methods of manufacturing shoes which consists in securing together an insole, a shank stiffener and a heel and shank reinforcing piece to make a reinforced insole unit, 15 molding the shank portion of said unit to arch the same both longitudinally and transversely, said molding operation including an overmolding of said portions to compensate for reaction of the molded material, beveling opposite lateral edges of the 20 shank portions of the insole and the reinforcing piece, and thereafter placing the molded insole unit upon a last, lasting an upper and securing it to said unit, and completing the shoe.

27. A shoe bottom unit comprising an insole, a 25 reinforcing member for the heel and shank portions of the insole secured by means of adhesive to the insole, the shank portions of the insole and the reinforcing member being molded longitudinally to conform to the longitudinal curvature of 30 the bottom of a last and being overmolded transversely, and a longitudinally arched shank stiffener located between the insole and the reinforcing member, the forward portion of the reinforcing member being forked thereby providing 35 an open notch, and the forward extremity of the shank stiffener lying within said notch with its outer surface substantially flush with the outer surface of the adjacent portions of the reinforcing piece.

28. A shoe bottom unit comprising an insole, a reinforcing member for the heel and shank portions of the insole secured by means of adhesive to the insole, the shank portions of the insole and the reinforcing member being molded longitudinally to conform to the longitudinal curvature of 45 the bottom of a last and being overmolded transversely, and a longitudinally arched shank stiffener located between the insole and the reinforcing member, the forward portion of the reinforcing member being forked thereby providing a 50 notch, and the shank stiffener having a part of its rear portion embedded in the reinforcing piece and having its front portion located within said notch.

29. That improvement in methods of making reinforced insoles which consists in cutting out an insole, cutting out a reinforcing member having the same outline as the heel and shank portions of the insole, forming two apertures in the 60 reinforcing member spaced apart lengthwise of said member, applying a coating of adhesive to the reinforcing member and to the heel and shank portions of the insole, assembling a shank stiffener with the reinforcing member by inserting 65 the ends of the stiffener into said apertures, molding the insole and the reinforcing member to arch them longitudinally to correspond to the longitudinal curvature of a last bottom while overmolding them transversely to compensate for reaction of the molded material, and utilizing the molding pressure to secure the insole and the reinforcing member together.

30. That improvement in methods of making reinforced insoles which consists in cutting out 70

an insole, cutting out a member for reinforcing the heel and shank portions of the insole and forming apertures in said reinforcing member for receiving the opposite ends of a shank stiffener, inserting the opposite ends of a shank stiffener through the apertures in said reinforcing member assembling the stiffened reinforcing member and the insole with adhesive between them, and applying pressure to the assembled parts to secure them together and at the same time molding the shank portions of the reinforcing member and the insole to arch them longitudinally to correspond to the longitudinal curvature of a bottom of a last and to overmold them transversely to compensate for reaction of the molded material.

31. A shoe bottom unit comprising an insole and a reinforcing member secured by means of adhesive to the heel and shank portions of the insole and having two apertures spaced apart lengthwise of the reinforcing member, and a

shank stiffener located between the reinforcing member and the insole and having its opposite end portions confined within said apertures, the shank portions of the insole and the reinforcing member being molded longitudinally to fit a last 5 and being overmolded transversely.

32. That improvement in methods of making reinforced insoles which consists in securing together an insole, a reinforcing piece for the shank portion of the insole, and a shank stiffener, and 10 molding the reinforcing piece and the shank portion of the insole to impart thereto a longitudinal curvature corresponding to that of the shank portion of the bottom of a last for a shoe in which said parts are to be incorporated and a transverse 15 curvature in excess of that of said last bottom portion to allow for change of transverse shape subsequently to take place in said reinforcing piece and said insole portion.

20

JOHN M. WHELTON.

CERTIFICATE OF CORRECTION.

Patent No. 2,065,463.

December 22, 1936

JOHN M. WHELTON.

It is hereby certified that error appears in the printed specification of the above numbered patent requiring correction as follows: Page 5, second column, line 45, for the word "by" read but; page 8, second column, line 7, claim 25, for "operating" read operation; and that the said Letters Patent should be read with these corrections therein that the same may conform to the record of the case in the Patent Office.

Signed and sealed this 9th day of March, A. D. 1937.

(Seal)

Henry Van Arsdale
Acting Commissioner of Patents.
